UNITED STATES PATENT OFFICE.

BENNEVILLE L. SINGLEY, OF MEADVILLE, PENNSYLVANIA, ASSIGNOR TO KEY-STONE VIEW COMPANY, OF MEADVILLE, PENNSYLVANIA, A CORPORATION OF PENNSYLVANIA.

DESIGN FOR A STEREOSCOPE.

Application filed December 20, 1927. Serial No. 24,562. Term of patent 14 years.

To all whom it may concern:

Be it known that I, BENNEVILLE L. SINGLEY, a citizen of the United States, residing at Meadville, in the county of Crawford and State of Pennsylvania, have invented a new, original, and ornamental Design for a Stereoscope, of which the following is a specification, reference being had to the accompanying drawing, forming a part thereof, wherein—

Fig. 1 is a side elevation of a stereoscope, showing my new design.

Fig. 2 a plan view.

Fig. 3 a front elevation.

I claim:—

The ornamental design for a stereoscope as shown.

BENNEVILLE L. SINGLEY.
